United States Patent

Des. 238,365
Patented Jan. 6, 1976

238,365

PORTABLE HEATER

James F. Mariol, Cincinnati, Ohio, and Amos E. Chesnut, Columbus, Ind., assignors to Arvin Industries, Inc., Columbus, Ind.

Filed Sept. 23, 1974, Ser. No. 508,541

Term of patent 14 years

Int. Cl. D23—03

U.S. Cl. D23—122

Fig. 1

Fig. 2

Fig. 3

Fig. 4

Fig. 5

Fig. 6

FIG. 1 is a perspective view of a portable heater showing our new design;

FIG. 2 is a rear elevation thereof;

FIG. 3 is a top plan view thereof;

FIG. 4 is a side elevation showing the heater and stand in an alternate position;

FIG. 5 is a side elevation again showing the heater and stand in still another alternate position; and

FIG. 6 is a perspective view of a second embodiment of the design shown in FIG. 1.

We claim:

The ornamental design for a portable heater, as shown and described.
